Attorney

UNITED STATES PATENT OFFICE.

WILLIAM ADAM SOUDER, OF SHAMOKIN, PENNSYLVANIA.

MILK-BOTTLE CLOSURE.

Application filed November 3, 1926. Serial No. 146,001.

This invention has reference to an improved closure which is especially, but not necessarily, adapted for use upon milk bottles and similar containers.

5 Briefly, the invention relates to a structure of this kind which includes a pivotally mounted closing cap, an operating handle therefor, a supporting ring for the cap, and means for detachably connecting this ring 10 to the bead of the bottle.

The invention is characterized by simplicity of construction, inexpensiveness of manufacture, practicability in use, and ease of application and removal.

15 Other features and advantages will become apparent from the following description and drawings.

In the drawings:—

Figure 1 is a side elevational view of the 20 complete device.

Fig. 2 is a top plan view.

Fig. 3 is a central sectional view, and

Fig. 4 is an elevational view looking from right to left in Fig. 1.

25 Referring now to the drawings in detail, it will be seen that the reference character 1 designates the neck of the bottle, which supports the usual bead 2 at the top. The reference character 3 designates the swingable mounted cap which is of circular form and which is provided with an operating member 4 integrally extended to one side as better shown in Fig. 2. This member is made to provide a finger piece and is adapted to be pressed downwardly for moving the 35 cap to open position.

The cap cooperates with a ring 5 which rests upon the customary ledge bead 2 as better shown in Fig. 3. Connected to the ring 40 at diametrically opposite sides are small straps 6 which are riveted or otherwise connected with a resilient split band 7 which surrounds the bead as shown.

The straps are bent down over the bead 45 as represented in Fig. 4. The ends of the band are spaced apart the approximate distance indicated in the same figure and are connected together through the medium of a coiled spring 8. A substantially U-shaped 50 wire member 9 has its bight portion connected with the operating finger piece 4 and has its arms 10 provided with right angular-

ly disposed extensions 11 inserted into the coils of the spring 8.

In addition, there is a flat longitudinally bowed spring 12 riveted as at 13 to the free outer end of the operating member 4. The opposite end of this spring is located between the coiled spring 8 and bears against the bead of the bottle as represented in Fig. 4. Obviously, then, the cap and operating member are supported upon the U-shaped part 10 and the cap is maintained in closed position under the action of the spring 12. By depressing the end portion thereof, the 65 cap may be swung to open position.

From the description and drawings, it will be seen that I have evolved and produced a simple and inexpensive closure which may be snapped over the neck of the bottle for 70 temporary use. The device obviously serves to replace the ordinary pasteboard caps in the home. Obviously, the standing feature is convenient in the application and removal and sanitation in use.

Having thus described my invention, what I claim as new is:—

1. In a structure of the class described, a disk-like cap, an operating member carried thereby, a flat supporting ring for the cap, a split band adapted to surround the neck of a bottle, connecting means between the ring and band, a coiled spring connecting the ends of the band together, a U-shaped member connected with said spring and having its bight portion connected with said operating member, and a flat longitudinal spring connected with the operating member at one end and adapted to bear at its opposite end against the neck of said bottle.

2. In a closure for bottles, comprising, a split band, a ring internally supported by the band, a cap for disposition on the ring, said cap being provided with an operating member, a coiled spring for connecting the free ends of the split band, a supporting member depending from the operating member and provided with a lateral extension for pivotal association with the coiled spring, and means for retaining the cap in closed position on the ring.

3. In a closure for bottles comprising, a split band, a ring internally supported by the band, a cap for disposition on the ring, said

cap being provided with an operating member, a coiled spring for connecting the free ends of said band, a supporting member depending from the operating member and provided with a lateral extension for pivotal association with the coiled spring, and a flat spring having one end

thereof secured to the operating member, and disclosed in tensioned position between the coiled spring and the bottle, for normally maintaining the cap in closed position on the ring.

In testimony whereof I affix my signature.

WILLIAM ADAM SOUDER.
